By Attorney

UNITED STATES PATENT OFFICE.

ARTHUR J. BROWN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CONTROLLER.

Application filed December 3, 1920. Serial No. 427,990.

To all whom it may concern:

Be it known that ARTHUR J. BROWN, a citizen of the United States, residing at Milwaukee, in the county of Milwaukee and State of Wisconsin, has invented a certain new and useful Improvement in Controllers, of which the following is a specification.

This invention relates to switches or controllers. It may be applied in switches of 10 the type having an off or neutral position and two operative positions and particularly a first circuit-closing position and a second circuit-closing position. In certain relations it becomes desirable to prevent 15 movement of a switch from its off position into its second circuit closing position unless the switch has been first moved into its first circuit closing position. One of the 20 objects of this invention is the provision of means whereby the aforementioned result may be secured in a simple and efficient manner. Another object of the invention is the provision of means whereby this result may be attained in connection with ordinary 25 double-throw knife switches with little or no reconstruction of the switch itself. Other objects will appear hereinafter as the description of the invention proceeds.

The novel features of the invention will 30 appear from this specification and the accompanying drawings forming part thereof and disclosing one embodiment of said invention and all these novel features are intended to be pointed out in the claims.

35 In the drawings Fig. 1 is a side elevation of a switch mechanism embodying the invention, the housing being broken away. Fig. 2 is a plan view of the mechanism illustrated in Fig. 1, parts thereof being broken 40 away.

The invention has been shown in the drawings as it may be applied in connection with a knife switch 1. The switch may have any desired number of blades 2, only two 45 blades being illustrated in Fig. 2, the rest of the switch and housing-parts being broken away. The blades 2 are pivoted in a desired manner and are adapted to be swung up into engagement with the stationary contact clips 3, (see Fig. 1) and down into engagement with the stationary contact clips 4. In case the switch is used for starting 50 motors, the upper and lower positions of the movable member may be the starting and running positions respectively in accordance

with the legends on the drawing. The clips 3, 4 are mounted in any suitable manner on a base board 5, which may be in turn supported directly on a wall (not shown) or on an auxiliary base. The switch blades 2 60 are connected to operate in unison by means of the cross-bar 6 to which is fastened the handle 7, the latter extending through an opening 8 in the cover 9 of a housing 10.

The housing 10 is here shown as carrying 65 a pivot pin 11 which is preferably substantially in line with the axis of rotation of the blades 2. A movable member lever 12 is adapted to swing on the pivot pin 11 and is associated for movement with the operating means of the switch by a disengageable connection between it and the cross-bar 6. This disengageable connection comprises a tongue 13 at the end of the lever 12 adapted to enter a recess 14 in the cross-bar 6. The 70 lever 12 is provided with an extension 15 which when the lever 12, and therefor the operating mechanism of the switch, is in off position makes a positive angle with the horizontal. The extension 15 is provided 75 with a longitudinal slot 16. An inertia-member, here shown as including a roll 17, and a pin 18 adapted to move freely in slot 16. In order that the inertia-member may be better balanced, a roll 19 may be provided 80 at the other end of the pin 18 on the other side of the extension 15.

A stop 20, here shown as also mounted on the housing 10, is provided with a surface 21 substantially at right angles to the path 85 of movement of the roll 17 when the operating means is moved from the off to the running or second operative position, that is, towards the clips 4. The stop 20 is also provided with a surface 22 substantially 90 concentric with the pivot pin 11. The surface 22 is some distance radially beyond the center of the roll 17 when the operating means is in its off position.

A spring 23 is provided, one end 24 of 100 which, is fastened to the pin 11 and the other end 25 of which is disposed on the side of the lever 12 toward the first operative position of the switch.

The clips 3 are provided with terminals 105 and connectors 26 which may be connected to any desired device as for example, an auto transformer, heavy starting fuses or directly to the electrical supply lines, etc. The switch blades 2 may be electrically con- 110

connected by means of the terminals and connectors 27 to an electrical supply line for example, and the clips 4 may be electrically connected by means of the terminals and 5 connectors 28 either directly to a motor or other translating device, or through fuses to such devices. It may be stated that as far as the novel features of the present invention are concerned the electrical connections to the device with which the invention 10 is used are entirely immaterial.

The operation of the device disclosed is as follows:

If an operator attempts to move the 15 handle 7 in a downward direction, that is, toward the clips 4 this motion will be soon arrested by engagement of the roll 17 with the surface 21 of the stop if these parts are not already in contact. The operator 20 may, however, move the handle 7 in an upward direction and fully into engagement with the clips 3. Inasmuch as the lever 12 and extension 15 move with the movable switch member the extension 15 will rotate 25 90 degrees or an amount proportional to the angular movement of the handle 7, in a clock-wise direction. Inasmuch as the slot 16 now makes a negative angle with the horizontal the inertia-member 17 will 30 roll to the radially outer end of the slot 16. The spring 23 has meanwhile been wound up by the lever 12 and is preferably 35 of such strength that very little effort will be necessary to pull the blades 2 out of the clips 3. If now the operator quickly moves the operating handle in a downward or counter clock-wise direction the inertia-member 17, being at a higher gravity potential level when the extension 15 again 40 assumes a positive angle, will not have time to roll to its position in Fig. 1 and will not have reached the level of the surface 22 before it has passed the surface 21 in a counter clock-wise direction. It will 45 be seen that by the described motion the inertia-member is permitted to move out of the way of the stop at least a sufficient time to enable it to pass said stop, provided the motion from the first circuit closing 50 position to the second position is executed with sufficient rapidity, and this is of course desirable in case the switch mechanism is used for example, in starting motors. The spring 23 is designed to facilitate this 55 rapidity of movement, but it is clear that the device would be operable without this spring.

It should be understood that it is not desired that the invention claimed be limited 60 to the exact details of construction shown and described, for obvious modifications will occur to a person skilled in the art.

It is claimed and desired to secure by Letters Patent:

65 1. In a switch having operating means

having an off and a first and second operative position, a member movable with said operating means, a stop, an inertia-member movable with and with respect to said movable member to a position where it will 70 engage said stop when said operating means is moved from off toward said second position, said inertia-member moving to a position with respect to said movable member out of the way of said stop when said operating means is moved to said first position 75 whereby said operating means may be moved from said first position to said second position.

2. In combination with a switch having 80 an off position between a first and second operative position, means for preventing movement of the switch from the off position into said second position but permitting movement from said first position into 85 said second position, means having inertia movable with the movable element of said switch, and having a predetermined radius of movement when said element is moved from off position toward said 90 second position, a stop for engaging said inertia-means and preventing movement thereof to said second position and means whereby said inertia-means moves to a position of larger radius when said 95 movable element is moved to said first position.

3. A switch having operating means having an off and a first and second operative 100 position, a member movable with said operating means said member having a slot making a positive angle with the horizontal when said operating means is in off position, a stop, an inertia-member movable to a position in said slot where it will engage said 105 stop when said operating means is moved toward said second operative position, said inertia-member being movable to a position in said slot out of the way of said stop when said operating means is moved to said first 110 position, whereby said operating means may be moved from said first position to said second position.

4. A switch having a pivoted movable element disposed in a substantially horizontal 115 off position, a pivoted lever movable with said element, said lever being provided with a slot making a positive angle with the horizontal when said element is in off position, an inertia-member movable to an inner limiting position in said slot, a stop for engaging said inertia-member when in said inner position, whereby when said element is moved upwardly said inertia-member will move to an outer position out of the way of 120 said stop.

5. In combination with a switch having 125 an off position between a first and second operative position, means for preventing movement of the switch from the off position 130

tion into said second position but permitting movement from said first position into said second position comprising means having inertia movable with the movable element 5 of said switch, said means having a predetermined position when said movable element is in said off position, a stop for engaging said inertia-means if moved toward said second position, and means whereby 10 said inertia-means is permitted to move bodily to a different position with respect to said movable element when said movable element is moved to said first position.

6. In combination with a switch of the 15 type having an off and a first and second position and having a movable contact member operable by an insulating cross-bar, a housing for said switch, means mounted on said housing for preventing movement of 20 said switch into said second position without prior movement into said first position, and means including a disengageable connection between said means and said cross-bar, whereby said switch may be bodily 25 removed from said housing without disassembling said switch or any portion thereof.

7. In combination with a double throw 30 knife switch of the type provided with an insulating cross-bar for operating the knife blades, a housing for said switch, means mounted on said housing for preventing movement of said switch into said second position without prior movement into said first position, and means including a disengageable connection between said means and 35 said cross-bar, whereby said switch may be bodily removed from said housing without disassembling said switch or any portion thereof.

40 8. In combination with a pivoted switch of the type having an off and a first and sec-

ond operative position, a housing for said switch, means, including a lever pivoted to said housing substantially coaxial with the axis of rotation of said switch, for preventing movement of said switch into said second position, and a disengageable connection between said lever and said switch whereby said switch may be bodily removed from said housing without disassembling 45 said switch or any portion thereof.

9. In combination with a pivoted switch of the type having an off and a first and second operative position, means for preventing movement of said switch into said 50 second position without prior movement into said first position, and a disengageable connection between a portion of said switch and a portion of said means one of said portions having a tongue cooperating with a 55 recess in the other said portion whereby said means and said switch may be bodily separated without disassembling either said switch or said means.

10. In combination with a double throw 60 switch of the type having an off position between a first and second position and having a movable contact member operable by an insulated cross-bar, a housing for said switch, means mounted within said housing 65 for preventing movement of said switch into said second position without prior movement of said switch into said first position, and means including a disengageable connection between said means and said cross-bar, whereby said switch may be bodily 70 removed from said housing without disassembling said switch or any portion thereof.

In testimony whereof, the signature of the 80 inventor is affixed hereto.

ARTHUR J. BROWN.
